Primary Examiner — Michael C Stout*Assistant Examiner* — Fitzgerald L Butac(74) *Attorney, Agent, or Firm* — Michael J. Nickerson; Basch & Nickerson LLP(57) **CLAIM**

The ornamental design for an automatic locking differential, as shown and described.

DESCRIPTION

FIG. 1 is a perspective view of an automatic locking differential;

FIG. 2 represents a front view of the automatic locking differential;

FIG. 3 represents a right side view of the automatic locking differential;

FIG. 4 represents a rear view of the automatic locking differential;

FIG. 5 represents a left side view of the automatic locking differential;

FIG. 6 represents a bottom view of the automatic locking differential; and,

FIG. 7 represents a top view of the automatic locking differential.
